US00D874480S

(12) **United States Design Patent** (10) Patent No.: **US D874,480 S**
 Christie et al. (45) Date of Patent: ** Feb. 4, 2020

(54) **DISPLAY SCREEN OR PORTION THEREOF WITH GRAPHICAL USER INTERFACE**

(71) Applicant: **Apple Inc.**, Cupertino, CA (US)

(72) Inventors: **Benjamin Thomas Christie**, Santa Clara, CA (US); **Alden Maxwell Haley**, Mountain View, CA (US); **Per Lindgren**, Cupertino, CA (US); **Alexander Charles MacLean**, San Jose, CA (US); **Wyatt R. Mitchell**, San Francisco, CA (US); **Diego Monzon Del Pino**, Cupertino, CA (US); **Allison Styer**, San Francisco, CA (US)

(73) Assignee: **Apple Inc.**, Cupertino, CA (US)

(**) Term: **15 Years**

(21) Appl. No.: **29/649,951**

(22) Filed: **Jun. 4, 2018**

(51) LOC (12) Cl. **14-04**

(52) U.S. Cl.

USPC **D14/485**

(57) **CLAIM**

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof, and form no part of the claimed design.

The text, symbols, and icons illustrated in broken lines form no part of the claimed design.

1 Claim, 1 Drawing Sheet
